Attorney.

UNITED STATES PATENT OFFICE.

WILLIAM BUHL, OF FLUSHING, NEW YORK, ASSIGNOR TO BULKRUG MACHINE CORPORATION, A CORPORATION OF NEW YORK.

CAM.

1,349,661.

Specification of Letters Patent. Patented Aug. 17, 1920.

Application filed September 12, 1919. Serial No. 323,332.

To all whom it may concern:

Be it known that I, WILLIAM BUHL, a citizen of the United States, and a resident of Flushing, in the county of Queens and State 5 of New York, have invented an Improvement in Cams, of which the following is a specification.

My invention relates to cams and it has for its object to provide a cam member having a cam contour with which is adapted to 10 cooperate a revolving driving member, the said driving member operating to effect percussive motion of the cam member, the said cam contour being provided with means 15 whereby, at the end of the percussive stroke or movement of the said cam device, the latter is free from the said driving member.

Other objects and advantages of my invention will be referred to in the detailed 20 description thereof which follows or will be apparent from such description.

In order that my invention may be readily understood and its practical advantages 25 fully appreciated, reference may be had to the accompanying drawing in which I have illustrated one convenient form of embodiment thereof.

In the drawing:

Figure 1 is a view in side elevation of a 30 cam device provided with a cam contour constructed in accordance with my invention and showing also a portion of a connection leading to a hammer or other tool or member, and also showing a revolute means 35 for driving the said cam device; and

Fig. 2 is a diagram illustrating the movements of the cam device effected by the revolution of the said driving means situated in the said cam contour.

Referring to the drawing: 1 designates a 40 cam device or member provided with a cam contour consisting, in the construction shown, of a slot, one portion 2 of which is of arcuate shape, while another portion 3 thereof is straight and may be described 45 as being in tangential relation with respect to the arcuate shaped portion 2.

The straight portion 3 may be of any 50 length desired and instead of terminating with the edge of the cam device or member 1, as is shown at 4 in Fig. 1, said straight portion of the slot may be extended to and through the end of said member. Such construction, however, would unnecessarily 55 weaken the cam member 1 and consequently

the latter would usually be selected of a size to permit the provision of a straight portion 3 wholly within the same, of such length as might be found to be desired or required. The straight portion 3 of the cam slot 60 constitutes the upper portion of said slot. The lower end of said portion is indicated by the horizontal dot and dash line *a*—*b* in Fig. 1, a short distance below the points of contact of the said pin with the slot at the moment 65 of completion of the locking movement of the cam device or member 1. It is at this moment that the impact of the hammer or other tool or member should take place.

The cam device or member 1 which is provided with a connection partially indicated at 5 for connecting it with a hammer or other member or device is adapted to be actuated by the reciprocating percussive motion of the said cam device or member. 70

The cam device or member is driven by 75 means of a crank pin 10 rigidly secured upon the revolute disk 11. Said crank pin projects into the cam slot, comprising the parts 2 and 3, and the cylindrical sleeve 12 80 thereon engages the opposite sides of the arcuate shaped portion 2 of the said cam slot. The disk 11 revolves with uniform speed.

Revolution of the crank pin effects percussive or quick-return motion of the cam device or member 1 to effect percussive action of the hammer or other member connected therewith. 85

The relative speeds of movement of the 90 cam member 1 resulting from the revolute movement of the crank pin 10 in the cam slot thereof are indicated in Fig. 2. Assuming that the crank pin occupies the position indicated at 1 at the right hand side of said 95 figure, which is the position it occupies at the moment of impact, and that the crank disk and pin are revolving in the direction of the hands of a clock, it will be noted that movement of the crank pin on the dot and 100 dash circle 14 from the point 1 to the point 2 causes vertical, upward movement of the cam device from the point 1 to the point 2, indicated on the straight, vertical dot and dash line 15. Relatively slow vertical, upward movement of the cam device or member 1 continues to the point 9 upon said line 15 during movement of the crank pin along the circle 14 to the point 9 thereon. Further movement of the crank pin to the right 110

from the point 9 on the circle 14 causes vertical movement downward of the cam member from the point 9 on the line 15 first to point 10, then to the point 11, then to point 12, and finally to the point 1 thereon; the entire vertical downward movement taking place during a movement of the crank pin 10 through a distance of substantially one third of a revolution. The complete vertical upward movement of the cam member is effected during the movement of the crank pin through the remaining two-thirds of a revolution.

It will be seen, therefore, that the cam member together with any tool or other member actuated thereby is moved with relatively great speed downwardly and with relatively slow speed in the opposite direction.

20 In the construction shown, the cam contour consists of a slot through the cam device or member 1 which is so proportioned and related with respect to the crank pin 10 that at the moment of impact or percussion of 25 the hammer or other member actuated by said device, the said crank pin 10 and sleeve 12 thereon are situated slightly within the lower end of the straight portion 3 of said cam contour. The result is that at such moment the crank pin is wholly free from and is in released relation with respect to the 30 said cam device or member 1. In consequence of this released relationship at this particular moment, the crank pin is not subjected to the reaction effects of the impact 35 of the hammer or other tool or member. The result is that a great deal of jarring and jolting due to the impact of the hammer or other tool or member is eliminated. The 40 said cam member being free to move independently of the said crank pin, the vibrations of the former are not interfered with by the latter, and consequently the effect of the vibrations of the hammer or other tool 45 or member upon the apparatus in which the said cam device or member and hammer or other member are embodied is reduced to a minimum.

In Fig. 1 I have shown the crank pin and 50 sleeve in dotted lines well within the straight part 3 of the slot to indicate that there may be relatively great relative, independent movement of the cam device 1 and said crank pin and sleeve in case the cam device and 55 hammer or other member operated thereby should move through an abnormal distance downwardly.

It will be seen that I have provided a cam construction by the employment of which a 60 percussive effect such as a hammer blow can be effected. Such a percussive effect can be produced only by the employment of an elastic system. A non-elastic system produces a squeezing or pressing effect.

65 As far as I am aware, those mechanisms

in the prior art that actually produce a percussive effect comprise in their construction an elastic element such as a spring or an air cushion. All attempts heretofore made to produce a percussive effect with a non-elastic mechanism have failed. Those elastic mechanisms which employ springs and air cushions are elastic through the whole cycle of the percussive motion. At the moment of striking the blow in such mechanisms, the percussive effect is restrained to a considerable extent by the dampening effect of the spring or air cushion, whichever may be employed. The ideal mechanism of this type should produce a sling-shot effect; that is, 70 the hammer or other member should be positively driven up to the moment of striking, but at such moment the said hammer or other member should be wholly unrestrained. A cam constructed in accordance with my invention complies with these ideal requirements of positive driving by non-elastic means except at the moment when the blow is struck. At or during this brief period of time, the driven member is wholly released 75 from the driving member and thereafter the percussive effect is wholly unrestrained. A cam device constructed in accordance with my invention may be employed in mechanism designed for numerous and various 80 purposes, as for instance, in riveting, chipping and calking hammers, hammer-type rock drills, shaking and impact screens, conveyors of the shaking trough type, concentrating tables, etc.

I claim:

1. A cam member provided with a cam contour, said cam contour consisting of an arcuate part adapted to convert uniform rotary motion into rectilinear quick-return motion, and a straight part adjoining one end of the said arcuate part and constituting a continuation of said cam contour.

2. A cam member provided with a cam contour comprising a curved part proportioned to translate rotary crank motion into percussive reciprocating motion and also comprising a part at one end which is continued in a direction tangent to the adjoining end of the curved part and parallel 110 to the path of movement of said cam member.

3. A cam member provided with a cam contour comprising a quadrantal shaped part proportioned to translate uniform rotary 115 crank motion into percussive reciprocating motion, and a part continued from one end of the said quadrantal-shaped part in a straight cam path which is adapted to release a crank from percussive re-action at 120 the end of the stroke of said cam member.

4. A cam member provided with a cam contour comprising a quadrantal shaped part proportioned to translate uniform rotary 125 crank motion into percussive reciprocating motion.

motion and a straight portion situated at the impact end of the stroke of said cam member, said straight part being continued as a tangent cam path parallel to the path of reciprocating motion of the cam member.

5. A cam member provided with a cam contour which is adapted to be engaged by a rotary driving member which is adapted to move with uniform speed, the said contour 10 comprising an arcuate part proportioned to translate the motion of said rotary driving member into rectilinear reciprocating motion, and a straight part, the latter part adjoining the upper end of the former part 15 and constituting a continuation of the said cam contour in the direction of the rectilinear reciprocating motion of the said cam member.

6. A cam member provided with a cam slot adapted to be engaged by a revoluble 20 driving member, the said cam slot comprising an arcuate portion with the opposite sides of which the said driving member is adapted to contact to effect rectilinear reciprocatory motion of said cam member; and 25 a portion of a width such that when the said driving member is situated therein the said cam member is free to move independently of the driving member, the said second named portion being situated at one end of 30 said arcuate portion and constituting a continuation thereof.

In testimony that I claim the foregoing as my invention, I have hereunto signed my name this 26th day of August A. D., 1919.

WILLIAM BUHL.
